UNITED STATES PATENT OFFICE.

JOHANN SUCHY, OF FRANKFORT-BOCKENHEIM, GERMANY, ASSIGNOR TO GENERAL ELECTRIC COMPANY, A CORPORATION OF NEW YORK.

ARC-POSITIONING DEVICE.

1,203,433.

Specification of Letters Patent.

Patented Oct. 31, 1916.

Application filed June 6, 1913. Serial No. 772,105.

To all whom it may concern:

Be it known that I, JOHANN SUCHY, a subject of the Emperor of Austria-Hungary, residing at Frankfort-Bockenheim, Germany, have invented certain new and useful Improvements in Arc-Positioning Devices, of which the following is a specification.

My invention has reference to an arc positioning device, and has for its object an improvement in a device of this character.

In search lights or projectors, where reflectors are used and where the source of light is an arc, it is important to keep the arc focused with reference to the reflector. The electrodes are usually both fed together or apart in step, and the feeding mechanism so arranged with reference to the sizes of the two electrodes as to maintain the arcing tips of the two electrodes at substantially the same distance from the center of the reflector. It is well known, however, that the arc has a tendency to wander about the arcing faces of the electrodes, and thus to shift the crater, which is the principal source of light produced by the plain carbon electrodes which are ordinarily employed in searchlights, laterally from the axis of the lamp.

My invention provides means for adjusting the position of the arc, comprising a magnet which, in the embodiment here shown, is an elongated magnet partially surrounding one of the electrodes and manually operated means for imparting to said magnet at will a partial rotation in either direction and thereby positioning the arc. The magnet is, at the same time, movable along the axis of the electrodes so that the strength of the magnetic field may be varied in accordance with the requirements of the arc. By this combination of movements it is possible to keep the arc in that position which produces the best results.

For a fuller understanding of my invention, reference may be had to the accompanying drawings which show only so much of the lamp mechanism as is necessary to properly understand my invention.

Figure 1 is an end view, partially broken away, of a device embodying my invention and Fig. 2 is a plan view thereof.

In the drawings, 1 and 2 are the electrodes between which the arc is formed which are ordinarily composed of plain carbon when used in search lights or projectors, and 3 is

the casing for housing the lamp mechanism. A pair of brackets 4 are secured at the top of the casing and support at their lower ends a base plate 5. This plate is provided with a rack 6 for a purpose that will be more fully hereinafter explained, and it is also provided on its upper side with a dovetailed groove 7. A carriage 8, mounted upon the base plate 5, is provided with a lug 9 which is shaped to conform to the groove 7, so that the carriage is held to the base and movable along the same and along the axis of the searchlight. The carriage is provided with an upwardly extending frame or bracket 10 having a concave portion 11 at the upper side, with a groove in which an elongated segmental magnet 12, which I have here shown as a permanent magnet, is seated. The outer face of this magnet is provided with a toothed gear 13, which is engaged by a worm gear 15 through an opening 14 in the bottom of the concave portion of the frame or bracket 10. The worm gear 15 is carried by a shaft 16 which is suitably journaled in the frame 10 and which may be given a partial rotation in either direction about the axis of the electrodes from a point without the casing by means of an extensible shaft 17, which is connected to the shaft 16 by a universal joint 18. The shaft 17 is provided at its outer end, at a point without the casing, with a handle 19 by which such rotation may be manually produced by the operator at will. It will be seen that a rotary movement of the shaft 17 produces a movement of the magnet 12 about its own axis and the axis of the electrodes, and by such movement the arc may be positioned by being repelled and driven to any point desirable on the arcing face of the electrodes. The carriage is also provided with a pinion 20 mounted in the frame of the carriage and in a special bracket 21. The shaft on which the pinion 20 is mounted is rotatable by means of an extensible shaft 22 connected to the shaft of the pinion 20 by a universal joint 23. The outer end of the shaft 22 is provided with a handle 24 by which the shaft 22 and the pinion 20 may be rotated, and it is obvious that by rotating the pinion 20 the carriage is moved along the base plate 5 and the magnet 12 moved longitudinally along the axis of the electrodes.

In accordance with the provisions of the

patent statutes, I have described the principle of operation of my invention, together with the apparatus which I now consider to represent the best embodiment thereof; but 5 I desire to have it understood that the apparatus shown is only illustrative, and that the invention can be carried out by other means.

What I claim as new and desire to secure by Letters Patent of the United States, is:—

10 1. In an arc lamp, a pair of electrodes, a blow magnet located to one side of the axis of the electrode, and manually operated means for imparting to said magnet at will a partial rotation in either direction and 15 thereby positioning the arc.

2. In an arc lamp, a pair of electrodes, a blow magnet located to one side of the axis of the electrodes, means for rotating said magnet about said axis, and means for 20 moving said magnet longitudinally of said axis.

25 3. In an arc lamp, a pair of axially alined electrodes, a segmental magnet partially surrounding one of the electrodes, manually operated means for imparting to said magnet at will a partial rotation in either direction about the axis of the electrodes, and thereby positioning the arc.

30 4. In an arc lamp, a pair of axially alined electrodes, a curved elongated blow magnet partially surrounding one of the electrodes, means for rotating said magnet about the axis of the electrodes, and means for moving said magnet longitudinally along the 35 electrodes.

40 5. In an arc lamp, a pair of axially alined electrodes, a segmental blow magnet having its axis substantially concentric with the axis of the electrodes, means for rotating said magnet about its own axis, and means

for moving the same longitudinally along the axis of the electrodes.

6. In an arc lamp, a pair of axially alined electrodes, a casing for housing the lamp mechanism, a segmental magnet substantially concentric with the axis of the electrodes, means operable, from without the casing for rotating said magnet about the axis of the electrodes, and other means operable from without the casing for moving 45 said magnet longitudinally along the axis of the electrodes.

7. In an arc lamp, a pair of axially alined electrodes, a segmental magnet provided with a toothed gear, a carriage for supporting said magnet, means comprising said toothed gear for rotating said magnet about the axis of the electrodes, and means for moving said carriage parallel to the axis of the electrodes.

55 8. In an arc lamp, a pair of axially alined electrodes, a segmental magnet substantially concentric with the electrodes, a carriage for supporting the same, means for rotating said magnet about the axis of the electrodes, and means for moving the carriage parallel to the axis of the electrodes.

60 9. In an arc lamp, a pair of electrodes, a carriage movable along the axis of said electrodes, a magnet supported on said carriage laterally of the electrodes, means for rotating the magnet about the axis of the electrodes, and means for moving the carriage along the axis of said arc lamp.

65 In witness whereof, I have hereunto set 75 my hand this fifteenth day of May, 1913.

JOHANN SUCHY.
